DESIGN FOR A TOY BUILDING BLOCK

Castro M. Dabrohua, Winnetka, Ill.

Application March 12, 1945, Serial No. 118,428

Term of patent 14 years

(Cl. D34—15)

To all whom it may concern:

Be it known that I, Castro M. Dabrohua, a citizen of the United States, residing at Winnetka, in the county of Cook and State of Illinois, have invented a new, original, and ornamental Design for a Toy Building Block, of which the following is a specification, reference being had to the accompanying drawing, forming a part thereof.

In the drawing:

Figure 1 is a top plan view of a toy building block, showing my new design; and

Figure 2 is a front elevational view thereof.

The reverse side of the toy building block is the same as the side that is shown in Figure 2.

I claim:

The ornamental design for a toy building block, substantially as shown and described.

CASTRO M. DABROHUA.
